UNITED STATES PATENT OFFICE.

ALFRED C. DAVIS, OF GAFFNEY, SOUTH CAROLINA.

WASHING MACHINE.

Application filed November 16, 1922. Serial No. 601,345.

To all whom it may concern:

Be it known that I, ALFRED C. DAVIS, a citizen of the United States, residing at Gaffney, in the county of Cherokee and 5 State of South Carolina, have invented a new and useful Washing Machine, of which the following is a specification.

The device forming the subject matter of this application is a washing machine, and 10 the invention aims to provide novel means whereby, through the instrumentality of a plunger mounted to oscillate in an orbit water, steam and air will be forced through the clothes to effect a cleaning thereof, novel 15 means being provided whereby a pair of such plungers may have alternating oscillation, one of the plungers being adapted to move within the curve of the body of the machine, and the construction of the device 20 being such that the clothes will not be dragged back in the body of the machine when the plungers are retracted.

With the above and other objects in view, which will appear as the description proceeds, the invention resides in the combination and arrangement of parts and in the details of construction hereinafter described and claimed, it being understood that, within the scope of what is claimed, changes in 30 the precise embodiment of the invention shown can be made without departing from the spirit of the invention.

In the accompanying drawings:—

Figure 1 shows in longitudinal section, a 35 device constructed in accordance with the invention; Figure 2 is a cross section taken through one of the plungers and illustrating the construction of both of them; Figure 40 3 is a section on the line 3—3 of Figure 1; Figure 4 is a fragmental horizontal section.

The machine comprises a casing or frame 1 embodying a back 2, a front 3 of less height than the back, ends 4 and a bottom 45 5, the ends 4 being reduced in width at their upper ends to form a correspondingly reduced upper compartment 6. A tubular body extends between the ends, 4 and is made up of an arcuate front member 7 and an arcuate rear member 8, spaced to form 50 an upper opening 9 and a lower opening 10 in the body of the machine. The members 7 and 8 of the body of the machine have

longitudinal corrugations comprising radial portions 12 and circumferential portions 14, 55 the corrugations on the member 7 being so arranged that when the clothes are moved in the direction of the arrow in Figure 3, the clothes will be prevented from moving downwardly and backwardly, the corrugations on the member 8 being so arranged 60 that they will prevent the clothes from moving upwardly and backwardly. Openings 15 are fashioned in the radial portions 12 of the corrugations, and when water passes 65 through the openings 15 from the casing 1 into the tubular body, the water will be discharged into the body circumferentially thereof and aid in moving the clothes correspondingly. Access is had to the body of 70 the machine by means of a lid 16 hinged at 17 to the member 7, portions of the ends 4 and of the front 3 forming an apron 22 serving to return to the body of the machine, water which may find its way above 75 the lid 16. The front wall 18 of the upper compartment 6 is hingedly mounted as at 19, and may be opened when desired. The compartment 6 is closed at its upper end by a top 20 hinged at 21 to the back 2. A 80 pocket 28 is carried by the back 2 and in the back there are openings 29 communicating with the pocket and with the interior of the casing 1. The pocket 28 and the openings 29 form means whereby water may be 85 introduced into the casing 1, and through the openings 29, the steam may escape. One end 4 of the casing 1 has a drain cock 23 through which water may be drawn off. The casing 1 carries a frame 27 including 90 lower bars 24 and upper bars 25 which are connected as indicated at 26, the bars 24 and 25 serving to reinforce the casing and forming a place of mounting for one of the plungers hereinafter described. The frame 27 95 may be used to support a motor (not shown) should it be desired to operate the machine by means of a motor mounted thereon.

The member 8 of the body has ends 30 provided with flanges 32 connected to the 100 ends 4 of the casing 1 and spaced therefrom, as shown in Figure 4, to receive arms 33 carrying an arcuate hollow plunger 34, the arms being mounted on pivot members 31 carried by the parts 30, 4 and 24. At its forward end, the plunger 34 is open, but is 105

guarded by a screen 35. The rear end of the plunger 34 carries a valve 36 adapted to close when the plunger moves in the direction of the arrow in Figure 3, and to open 5 when the plunger moves in an opposite direction. Pitmans 37 are connected pivotally with the arms 33 of the plunger 34 and are assembled with cranks 38 on a shaft 39 located in the compartment 6 and journaled in 10 bearings 50 on the ends 4 of the casing 1. Although the shaft 39 is shown as rotated by a pulley 40, any other suitable means may be supplied for operating the shaft, by hand or otherwise. The shaft 39 has an intermediate crank 41 connected by a pitman 42 with an arcuate plunger 43 constructed like the plunger 34, the arms 44 of the plunger 43 being mounted pivotally, as at 45, on the back 2. The cranks 41 and 38 are set 180 15 degrees apart, and it will be obvious that when the plunger 34 is advanced, the plunger 47 will be retracted, and when the plunger 47 is advanced, the plunger 34 will be retracted, the plunger 34 operating through 20 the opening 10 in the body of the machine, the plunger 47 operating in the opening 9 of the body of the machine, the plunger 34 being mounted at 31 to move in an arc which is not coincident with the curve of the members 7 and 8 of the body. The plungers, 25 co-acting with the corrugations on the body, exert a rubbing action on the clothes, and the plungers, further tend to force the water through the clothes. When the plungers 30 move rearwardly, taking the plunger 34 of Figure 2 as typical, the valve 36 will open, and this valve is of such size that the plunger 35 will fill readily, and any air which may have

been trapped in the plunger will find a ready 40 exit.

I claim:—

1. In a washing machine, a tubular body having openings, arcuate plungers, means for mounting the plungers for movement through the openings, and means for reTRACTING one plunger whilst the other plunger is being advanced, the body being provided, on its opposite sides, with corrugations, the corrugations on both sides of the body comprising substantially radial portions, the corrugations on one side of the body comprising portions which slant downwardly and outwardly, and the corrugations on the other side of the body comprising portions which slant downwardly and inwardly. 45 50 55

2. In a washing machine, a casing and a tubular body positioned in the casing, the body having an opening in its bottom and provided with an opening in its top; an arcuate plunger; means for mounting said plunger for movement through the bottom opening, in a direction circumferentially of the body; a second arcuate plunger; and means for mounting the second plunger for movement through the top opening, downwardly and outwardly toward a side wall of the body. 60 65

In testimony that I claim the foregoing as my own, I have hereto affixed my signature in the presence of two witnesses. 70

ALFRED C. DAVIS.
